(Cl. D34—15)

To all whom it may concern:

Be it known that I, Nicholas T. Baldanza, a citizen of the United States and resident of Rutherford, in the county of Bergen, State of New Jersey, have invented a new, original, and ornamental Design for Rope-Jumping Figure Toy, of which the following is a specification, reference being had to the accompanying drawing, forming a part thereof, and of which

Fig. 1 is a front elevational view of the rope-jumping figure toy, showing my new design;

Fig. 2 is a top plan view thereof; and

Fig. 3 is a side elevational view thereof.

I claim:

The ornamental design for a rope-jumping figure toy, as shown.

NICHOLAS T. BALDANZA.
